UNITED STATES PATENT OFFICE.

EARL C. BOOTH, OF INDIANAPOLIS, INDIANA, ASSIGNOR TO HOLCOMB & HOKE MFG. CO., OF INDIANAPOLIS, INDIANA, A CORPORATION.

DESIGN FOR A VENDING-MACHINE HOUSING.

Application filed February 5, 1923. Serial No. 5,078. Term of patent 7 years.

To all whom it may concern:

Be it known that I, EARL C. BOOTH, a citizen of the United States, residing in the city of Indianapolis, county of Marion, and State of Indiana, have invented a new, original, and ornamental Design for a Vending-Machine Housing, of which the following is a specification, reference being had to the accompanying drawings, forming a part thereof.

In the drawings Fig. 1 is a front elevation of the housing. Fig. 2 is a section taken on the line 2—2 of Fig. 1 showing my new design.

I claim:

The ornamental design for a vending machine housing, as shown.

EARL C. BOOTH.
